Primary Examiner — Susan E Krakower*Assistant Examiner* — Lisa A Grabenstetter(74) *Attorney, Agent, or Firm* — Jianq Chyun IP Office(57) **CLAIM**

The ornamental design for an electronic instrument with keyboard, as shown and described.

DESCRIPTION

FIG. 1 is a perspective view of an electronic instrument with keyboard showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partially enlarged end view of the cross-section taken along line 9-9 of FIG. 6;

FIG. 10 is a partially enlarged end view of the cross-section taken along line 10-10 of FIG. 6; and,

FIG. 11 is a partially enlarged end view of the cross-section taken along line 11-11 of FIG. 6 with the internal structure simplified.

The broken line portions show unclaimed subject matter only and form no part of the claimed design. The dot-dash broken lines in FIG. 6 are included to show cross-sections only and form no part of the claimed design.

1 Claim, 11 Drawing Sheets(56)
